(57) **CLAIM**

The ornamental design for a mailing wrapper, as shown and described.

DESCRIPTION

FIG. 1 is a top plan view of a mailing wrapper showing my new design, in a closed configuration;

FIG. 2 is a left side view thereof, the right side view being a mirror image thereof;

FIG. 3 is a left side view thereof in a partially open configuration, the right side view being a mirror image thereof;

FIG. 4 is a left side view thereof in a fully open configuration, the right side view being a mirror image thereof;

FIG. 5 is a front perspective view thereof in a partially open configuration;

FIG. 6 is a front perspective view thereof in a fully open configuration; and,

FIG. 7 is a rear view thereof in a fully open configuration.
